CONTINUOUS BEATER AND PULP SELECTOR

Harold Donald Wells, Glens Falls, N. Y.

Application April 16, 1941, Serial No. 388,878

2 Claims. (Cl. 92—23)

The invention aims to provide a new and improved machine for converting various kinds of paper-making materials and the like into pulp suitable for paper-making, and for continuously discharging the screened pulp, the construction being such that a single rotor acts not only to beat and circulate the stock-treating liquid, but acts also to keep the screen clean to permit continuous discharge of the pulp as it is reduced to the desired state of fineness.

With the foregoing in view, the invention resides in the novel subject matter hereinafter described and claimed, description being accomplished by reference to the accompanying drawing.

Figure 1 is a vertical sectional view partly in elevation.

Figure 2 is an enlarged vertical sectional view through the lower central portion of Fig. 1.

Figure 3 is a top plan view of the rotor.

Figure 4 is a detail horizontal section on line 4—4 of Fig. 1.

A preferred construction has been illustrated and will be rather specifically described, with the understanding, however, that within the scope of the invention as claimed, variations may be made.

A large tank 5 is provided having a feed hopper or the like 6 through which to feed the stock from which the pulp is to be formed, and at 7 I have illustrated an inlet pipe for the stock-treating liquid, and obviously the supply of both stock and liquid, or either of them, may be automatically controlled, if desired. At the juncture of the tank bottom 8 with the tank side wall, the tank is preferably provided with a curved continuous portion 9 which curves upwardly from said bottom to said side wall to facilitate the outward, upward and inward circulation of pulp illustrated by the arrows in Fig. 1. The part 10 shown in Fig. 1 is simply a cover plate for a tank cleanout hole.

The tank bottom 8 is formed with a central opening 11 of preferably circular outline, and through this opening, a vertically disposed cylindrical casing 12 passes, said casing having a fluid-tight connection with the tank bottom which preferably includes a peripheral flange 13 on said casing suitably secured to said bottom. The major portion of the casing 12 is in the form of a pan disposed principally below the tank bottom 8 and provided with a screened pulp discharge pipe or the like 14. The bottom of this major casing portion rigidly carries a central upstanding sleeve 15 and the upper end of this sleeve

carries the upper end plate 16 of the casing, this end plate being upwardly spaced from the upper edge of the pan-like lower portion of the casing as shown in Fig. 2. At the periphery of the casing, a cylindrical screen 17 extends between the casing top plate 16 and the pan-like lower portion of the casing and is suitably secured to one or both thereof. This screen is preferably detachable to permit removal of a screen having one degree of fineness and substitution of another having a different degree of fineness, according to the state to which the pulp is to be reduced before discharge.

A vertical shaft 18 extends upwardly through the sleeve 15 and is rotatably mounted in any appropriate bearing assembly 18^a secured in said sleeve. The upper end of shaft 18 carries a rotor 19 which is disposed directly over the casing top plate 16, said rotor being substantially conical. The top of this rotor is provided with a plurality of blades 20 which beat the pulp and impel it outwardly so that it will be caused to circulate as indicated by the arrows in Fig. 1, said blades being preferably of spiral form as shown in Fig. 3. The rotor 19 also carries at least one and preferably a plurality of downwardly projecting arms 21 which are disposed at the periphery of the screen 17 in slightly spaced relation with this screen, said arms serving to keep the screen clean. The arms decline rearwardly with respect to their direction of travel and are thus self-cleaning. These arms also diverge rearwardly from the screen 17 with respect to their direction of travel, as seen in Fig. 4. Thus, they will outwardly force the fluid pulp away from the screen and this pulp will immediately flow inwardly behind the arms, thus producing pulsation of the pulp radially of the screen to facilitate pulp discharge and to aid also in keeping the screen clean.

Any desired means may be provided for rapidly driving the rotor 19 and for this purpose, I have illustrated a multiple V-belt drive 22 connecting the lower end of the shaft 18 with an electric motor 23.

In operation, while the rotor is being rapidly driven, the stock and liquid for treating same are caused to circulate as shown by the arrows in Fig. 1 and during this circulation, the blades 20 perform an effective pulp beating operation to reduce the pulp forming material as required, and as this material is sufficiently reduced, it continuously discharges through the screen 17. The arms 21 pulsate the pulp radially of the screen and serve as cleaners for the latter. The pulp-

ing and screened pulp discharge operations may be continuously performed for any desired length of time, or if desired, the apparatus could be used for carrying out a batch process of pulp reduction instead of a continuous process. If the process is to be continuous, the stock is preferably automatically fed through the hopper 6 and the stock treating liquid is automatically fed through the pipe 7.

From the foregoing taken in connection with the accompanying drawing, it will be seen that novel and advantageous provision has been made for carrying out the object of the invention, and while preferred structural features have been illustrated, attention is again invited to the possibility of making variations within the scope of the invention as claimed.

I claim:

1. A paper-making-pulp beater and selector comprising a liquid and stock tank, a cylindrical pulp discharge screen disposed centrally of said tank and projecting upwardly from the tank bottom, said cylindrical screen having its axis disposed vertically and having its outer periphery directly exposed to the contents of said tank, a rotor over and in close proximity to said cylindrical screen and mounted on a vertical axis in concentric relation with said cylindrical screen, pitched blades secured to said rotor for beating the tank contents and centrifugally moving the same to produce an outward, upward, inward and downward circulation, and an arm secured to said rotor and projecting downwardly therefrom at the outer periphery of said screen, said arm

serving to clean said screen and to radially pulsate the pulp immediately surrounding said screen, and means under said tank and communicating with the interior of said cylindrical screen for receiving the screened pulp discharging through said screen.

2. A paper-making-pulp beater and selector comprising a liquid and stock tank, the bottom of which is formed with a central opening, a lower cylindrical pan-like casing body the upper end of which is secured in said opening, said casing body having an outlet for the screened pulp located below said tank bottom, a central vertical sleeve rigidly secured to the bottom of said casing body and projecting upwardly to a level above said body, a horizontal casing top plate centrally secured rigidly to the upper end of said sleeve, said top plate being of circular outline and having its edge disposed directly over the cylindrical side wall of said casing body, a cylindrical screen extending from said casing top plate to said cylindrical side wall, a bearing assembly secured in said sleeve, a vertical shaft extending through said sleeve and mounted in said bearing assembly, a rotor secured to the upper end of said shaft and directly overlying said top plate, said rotor having circulating and beating blades for the tank contents and also having a downwardly projecting arm for cleaning said screen and radially pulsating the pulp flowing therethrough, and means under said tank and connected with said shaft for driving the same.

HAROLD DONALD WELLS.
